CLAIM

The ornamental design for a monitor mount clamp, substantially as shown and described.

DESCRIPTION

FIG. 1 is a perspective view of a monitor mount clamp, showing our new design;

FIG. 2 is a top view thereof;

FIG. 3 is a bottom view thereof;

FIG. 4 is a front view thereof;

FIG. 5 is a back view thereof;

FIG. 6 is a right side view thereof; and,

FIG. 7 is a left side view thereof.

The broken lines show features or environment that form no part of the claimed design.

1 Claim, 7 Drawing Sheets
